UNITED STATES PATENT OFFICE.

SAMUEL DALIN, OF WEST ALLIS, WISCONSIN.

DESIGN FOR A FINGER RING.

Application filed August 9, 1923. Serial No. 6,988. Term of patent 7 years.

To all whom it may concern:

Be it known that I, SAMUEL DALIN, a citizen of the United States, residing at West Allis, in the county of Milwaukee and State of Wisconsin, have invented a new, original and ornamental Design for Finger Ring, of which the following is a specification, specific reference being had to the accompanying drawing, forming a part thereof.

The figure of the drawing is a perspective view of the ring constituting my new design.

I claim:—

The ornamental design for a finger ring, substantially as shown.

In testimony whereof, the signature of the inventor is affixed hereto.

SAMUEL DALIN.
